BROODER

Luty Hawkins, Mount Vernon, Ill., assignor to
 Hawkins Million Dollar Hen, Inc., Mount
 Vernon, Ill.

Application June 13, 1939, Serial No. 278,975

18 Claims. (Cl. 119—33)

This invention relates to brooders or hovers and more particularly to a collapsible brooder or hover.

An object of this invention is to provide a brooder of this character which is so constructed that it can be easily and quickly assembled so that the device may be initially produced and shipped in a knocked down form and then assembled by the purchaser without the use of any tools.

Another object of this invention is to provide in a brooder of this character an improved heating means whereby several ranges of heat may be provided.

A further object of this invention is to provide a brooder of this kind which includes vertical side walls and means suspended inwardly of the walls to provide a dead air space serving as an insulating means for the walls of the device.

A still further object of this invention is to provide a brooder of this character which is so constructed that it may be used for a longer period of time than brooders at present available, the device including means whereby the height of the brooder structure may be gradually increased as the chickens grow in height.

A further object of this invention is to provide a brooder of this kind which includes a novel heating means wherein a thermostat is so connected to the heating units or elements that a relatively small and cheap thermostat may be used.

A further object of this invention is to provide in a brooder of this type an improved means for supporting a heating device within the brooder.

A further object of this invention is to provide in combination a rectangular brooder frame structure and an insulated top which is adapted to retain the heat on the inside of the brooder, the insulation being of such a character that it may be readily replaced as occasion requires.

A further object of this invention is to provide in combination a brooder structure including an insulated top and a roost structure which is adapted to removably engage on the top wall of the device so that the chickens may be disposed above the warm top without coming into direct contact with the heat producing means.

A further object of this invention is to provide a brooder of this kind including fabric inner walls and novel means for supporting the inner walls within the frame structure, the inner walls being provided at their lower edges with depending flaps which may be readily pushed aside by

the chickens in either entering or leaving the device.

To the above and other objects which may hereinafter appear, the invention consists of the novel construction, combination and arrangement of parts as will be more specifically referred to and illustrated in the accompanying drawings wherein is shown an embodiment of this invention, but it is to be understood that changes, modifications and variations may be resorted to which fall within the scope of the invention as claimed.

In the drawings:

Figure 1 is a longitudinal section taken substantially on the line 1—1 of Figure 2 showing one portion of the top in elevated position;

Figure 2 is a transverse sectional view taken on the line 2—2 of Figure 1;

Figure 3 is an exploded plan view of the frame structure with the top removed;

Figure 4 is a detail side elevation partly in section of the heater;

Figure 5 is a sectional view taken on the line 5—5 of Figure 4;

Figure 6 is a diagrammatic view of the circuits embodied in the heater;

Figure 7 is a plan view of the device;

Figure 8 is a fragmentary end elevation of the device;

Figure 9 is a fragmentary sectional view taken on the line 9—9 of Figure 8;

Figure 10 is an enlarged fragmentary sectional view taken on the line 10—10 of Figure 7;

Figure 11 is an enlarged fragmentary sectional view taken on the line 11—11 of Figure 8; and

Figure 12 is a fragmentary plan view of one corner of the frame structure.

Referring to the drawings, the numeral 15 designates generally a rectangular frame structure which comprises a pair of oppositely disposed side walls 16 of like form and a pair of oppositely disposed end walls 17 of like form.

Each side wall 16 comprises an elongated upstanding plate or sheet of metal 18 formed respectively at each end with an outwardly directed flange 19, at its upper edge with an inwardly extending flange 20 and at its lower edge with an inwardly extending flange 21.

Each of the end walls 17 comprises a sheet of metal 22 which at its upper edge is provided with an angle member 23 and at its lower edge with a second angle member 24. The angle members 23 and 24 are adapted to be secured to the inner side of the plate 22 by spot welding 25 or the like. The end walls 17 at each vertical

edge thereof are provided with U-shaped guide members 26 within which a flange 19 is adapted to slidably engage. A vertically disposed angle member 27 has one side thereof welded or otherwise secured to the inner side of an end wall plate 22 and the other side of the angle member 27 is disposed in inwardly spaced relation to the free edge of the reverted or U-shaped guide member 26 so that when the side wall 16 is in assembled position the inwardly projecting side of the angle member 27 will hold the flange 19 against lateral movement relative to a guide member 26. In this manner a substantially L-shaped guide channel is provided at each vertical edge of an end wall member 17 which is adapted to receive a flange 19 so as to hold the side wall members 16 in assembled position relative to the end wall members 17. At each end the flange 20 of a side wall member 16 is cut off at an angle as at 28 and in like manner each end of an upper angle member 23 is cut off as at 29. The angle portion 28 of the flange 20 is adapted to rest on the upper end of an angle member 27 as shown in Figure 12 so as to thereby hold the side wall members 16 against further downward movement relative to the end wall member 17.

Each end wall member 17 is provided on the outer side thereof with a pair of vertically aligned guide members 30 within each pair of which a post or supporting leg 31 is adapted to slidably engage. The leg 31 between a pair of guide members 30 is provided with a laterally projecting arm 32 and the end wall 17 on the outer side thereof is provided with a plurality of vertically spaced apart and downwardly directed hooks or holding members 33 within a selected one of which the arm 32 is adapted to engage so that each leg or supporting member 31 may be adjusted so as to thereby raise or lower the frame structure comprising the sides 16 and the ends 17.

Each of the side wall members 16 at its upper edge is provided with an upwardly opening U-shaped channel member 34 which has an outwardly projecting portion 35 engaging beneath a flange 20 and secured thereto as by spot welding or the like. The channel or inner wall supporting member 34 projects inwardly of the flange 20 and the upper end of a flexible or fabric wall 36 is adapted to engage in the channel or supporting member 34. The inner wall 36 is constructed of substantially heavy cloth and is provided at its upper end with a tunnel or looped portion 37 within which a metal rod 38 is adapted to engage. In this manner the metal rod 38 will removably support the inner wall 36 from the channel member 34. The inner wall 36 is positioned in inwardly spaced relation to the outer wall 18 thereby providing a dead air space 39 forming an insulating chamber between the lower flange 21 and the upper flange 20. The inner wall 36 at a point adjacent the lower edge thereof is provided with a horizontally disposed tunnel or channel 40 within which a weighting means therefor in the form of a metal rod 41 is positioned. In this manner the wall 36 is held extended and adjacent the inner edge of the flange 21. A plurality of depending flaps 42 are secured at their upper edges to the lower edge of each inner wall 36 and these flaps 42 are adapted to overlap each other at their adjacent edges so that in normal position these flaps 42 constitute extensions of the side wall members 36. However, these flaps 42 are formed of substantially light weight material so that when the frame structure is in its lower-

most position, the small chickens may readily move out from within the frame structure by pushing the flaps outwardly and may return by an inward movement of the flaps 42.

5 The end walls 17 are provided at their upper edges with channel members 43 which are similar in construction to the channel members 34, being provided with an outwardly extending portion 44 engaging beneath the angle member 23 and secured thereto as by spot welding or the like. An end wall member 45 provided at its upper end with a tunnel or loop 46 is removably suspended from the channel member 43 and a metal rod 47 is disposed in the tunnel 46 so that 10 the inner end wall member 45 will be suspended from a channel member 43 and in inwardly spaced relation to the outer end wall member 22. The inner end wall member 45 is preferably longer in length than the inner end wall member 36 and 15 extends downwardly to a point slightly above and inwardly of the bracing or angle member 24 so as to thereby form an insulating air space 22. 20

25 The interior of the frame structure 15 is adapted to be maintained at the desired temperature by means of a heating device generally designated as 49. This heating device comprises a wire mesh horizontally disposed housing 50 provided with a removable wire mesh cover 51. The lower portion of the housing 50 is provided with a rectangular frame 52 having an inwardly projecting flange 53. The housing 50 is secured to the frame 52 by means of a plurality of clips 54 which are bent about the frame 52 and about the vertical side portions of the lower housing member 50. The heating member 49 at one end thereof is provided with a transversely disposed angle member 55 extending between the sides of the rectangular frame 52 and a plurality of insulated bushings 56 extend through the angle member 55. The end member 57 of the frame 52 is provided with an insulating bushing 58 through which a pair of wires 59 are adapted to engage. 30 The wires 59 constitute a means for connecting the hereinafter described heating unit to a source of electric current supply. An insulated plate 60 is secured to an inwardly projecting plate 61 carried by the end member 57 and secured between the sides of the frame 52. Terminals 62 are mounted on the insulated plate 60 and the two wires 59 are connected to these terminals 62. An intermediate angle member 63 extends between and is secured to the sides of the frame 52 and insulators 64 extend through the vertical side of the angle member 63. A third angle member 65 is positioned in spaced relation to the intermediate angle member 63 and insulators 66 extend through the vertical side of the angle 40 member 65.

60 The heating member 49 is provided at its forward end with a downwardly extending wire mesh housing 67 which is preferably formed integral with the lower housing portion 50. A thermostat generally designated as 68 is mounted within the housing 67 and is connected to the heating elements as will be hereinafter described.

A pair of longitudinally extending and outer heating elements 69 extend through the outer insulators 56, 64 and 66 and these heating elements 69 are connected together in series by conductors 70 and 71. One end of one heating element 69 is connected to one of the wires 59 and the other of the heating elements 69 is connected to the other 75 of the wires 59. The opposite ends of the two

outer heating elements 69 are connected through the conductors 70 and 71 to the thermostat 68. The inner ends of the two heating elements 69 are connected as by conductors 72 to the terminals 62.

The thermostat 68 comprises a horizontally disposed insulated plate 73 which is secured to a flange 53 at the end of the frame 52 opposite from the end member 57 and a depending supporting member 74 is secured to the insulated plate 73. A rocking member 75 of insulated construction is disposed on one side of a depending supporting member 74 and is provided at its lower end portion with a horizontally projecting stud 76 and one end of a coiled bi-metallic spring member 77 is secured to the stud 76. A contact 78 is carried by a vertical extension 79 integral with the coil member 77 and is normally adapted to contact with a stationary contact 80 carried by a support 81 fixed to the support 74. The thermostat adjusting lever or member 75 is rocked by means of a bell crank 82 having one portion thereof engaged with a loop 83 carried by the rock member 75. An adjusting lever 84 is secured to the bell crank 82 and is positioned above the insulated plate 73. A pair of spaced apart stop pins 85 are positioned on opposite sides of the adjusting lever 84 so as to limit the swinging movement of this lever. Rocking of the lever 84 will swing the insulated member 75 so as to either tighten the coil 77 or loosen this coil and thereby permit operation of the thermostat to cut on or off the heat at the desired temperature.

An inner pair of heating elements 86 extend through the inner insulators 56, 64 and 66 and one end of each heating element 86 is connected to a terminal 62, being connected in series. The opposite ends of the two inner heating elements 86 are connected to a switch 87 mounted on a supporting member 88 which is fixed to the angle member 65. The opposite ends of the heating elements 86 are connected as by conductors 89 to the switch 87 so that when the switch 87 is closed the two heating elements 86 are connected together in series but are not connected to the thermostat 68.

A light member 90 is mounted in a socket 91 carried by a transversely extending supporting plate 92 which is fixed to the frame 52. The socket 91 is connected as by a pair of conductors 93 to the two terminals 62 and is adapted to be lighted at all times when the heating member 49 is in operation. The heating member 49 is supported within the frame 15 by means of pairs of upwardly extending hooks 94 which are secured to the frame 52. The hooks 94 are adapted to engage downwardly projecting supporting members 95 provided with an opening 96. The supporting members 95 are secured in pairs to a transversely extending channel supporting bar 97. Each bar 97 at the ends thereof is provided with a downwardly extended threaded stud 98 which engages through an opening 99 provided in an inwardly projecting strip 100 which is secured to the under side of a flange 20.

Through the provision of threads on the studs 98 the supporting bars 97 are more readily held in applied or operative position than where unthreaded studs are used. With the use of threaded studs, it is not necessary to use cotter pins, nuts or the like to hold the bars 97 in operative position. These bars 97 also hold the side members 16 against spreading.

A removable top generally designated as 101 is mounted on top of the frame 15 and comprises a pair of bottom walls 102 and channelled side and

end walls 103 and 104. The two top sections 101 and 101a are in the form of open top chambers or containers hingedly connected together by a hinge structure 105 and each of the top sections 5 is provided with a supporting leg 106. The supporting leg 106 at its upper end has a V-shaped portion 107 engaging through the bight of a channel member 104 so as to pivotally secure a supporting leg to an end channel member 104 and permit the long leg portion 106 to extend downwardly and engage the upper edge of an end member 17. Each end member 17 is provided with a plate 108 which projects partly above the top of the end member and against which the lower end 15 of the supporting leg 106 is adapted to engage. This plate 108 also holds the top sections against endwise movement. The side wall members 16 are provided at a point in the longitudinal center thereof with an upwardly projecting plate 109 which plate 109 is adapted to hold the two top sections against lateral movement.

The top section 101 is provided with a transversely extending brace 110 which is shorter in height than the height of the side members 103. 25 In like manner, the top section 101a is provided with a channel member 110a. The top sections 101 and 101a are adapted to have substantially loose material 111 positioned therein which has a depth substantially equal to the height of the braces 110 and 110a. This material 111 may be in the form of peat moss or other suitable material which will serve as an insulating means to hold the heat from the heating member 49 in the frame 15. It will, of course, be understood that when the heating member 49 is in operation, the insulating material 111 will also be heated and when the chickens are large enough, they may roost on top of the frame structure. Preferably, a roost member in the form of a plurality of transversely extending parallel bars 112 secured to a rectangular frame 113 is adapted to engage on top of the two top sections 101 and 101a. This roost comprising the bars 112 and the rectangular member 113 is a rigid structure and the bars 112 are adapted to project laterally of the sides 16 for the desired distance so that the chickens may roost on the outer portions of these bars 112.

In the use and operation of this brooder, the device is initially shipped to the purchaser in knocked down condition with the sides, ends, heater and supporting means therefor disconnected. The sides and ends are assembled by positioning the flanges 19 in the channel members 26 at the upper ends of these channel members and then forcing the side members downwardly until the flange 20 engages the upper end of the angle member 27. The height of the frame 15 may be readily adjusted by adjustment of the supporting legs 31 through the medium of the hooks 33 and the hook engaging arm 32 carried by each leg 31. The heater may be suspended within the frame 15 by initially engaging the hooks 94 with the depending members 95 and then mounting the bars 97 on the inwardly projecting members 100 with the threaded studs 98 engaging in the openings 99.

The inner side walls 36 are mounted in the supporting channels 34 before the supporting bars 97 are in operative position. The inner end wall members 45 may then be mounted in the end channel members 43. The two wire conductors 59 may then be connected to a source of electric current supply and the top sections 101 and 101a then removably mounted on top of the frame 15.

In normal use the two top sections are in horizontal alignment with the legs or supporting members 106 positioned on the outer open side of the end channel members 104. The thermostat 68 may then be adjusted to produce the desired heat through the outer heating elements 69 which are connected together in series. When the chickens are within the frame 15 and it is found that the chickens are not obtaining enough heat, the inner heating members 86 may be connected through the closing of the switch 87 to the supply conductors 59 so as to thereby provide the desired additional heat.

After the chickens have grown the frame may be raised by adjusting the legs 31 and then the roost comprising the bars 112 and 113 may be loosely mounted on top of the two top sections 101 and 101a.

If it is desired to inspect the chickens on the inside of the frame 15 or inspect the heating member 49, one of the top sections may be swung upwardly and supported in upwardly inclined position by swinging a leg member 106 downwardly and engaging the lower end of the leg member 106 with an upwardly projecting plate 108.

A brooder constructed according to this invention may be constructed at a substantially small cost and due to the knocked down factor of the device, the entire structure may be shipped at a lower freight rate than where the brooder is completely assembled. In addition to this, the assembling of the brooder is a relatively simple matter and does not require the use of any tools whatsoever as the side walls readily slide into the end channel members 26 to the limit permitted by the upper ends of the inwardly projecting angle members 27. These angle members 27 not only serve as a means to limit the downward movement of the side walls 16 relative to the end walls 16, but also serve as a means to hold the flanges 18 in the channels 26 so that when the structure is in assembled condition, it will not collapse.

What I claim is:

1. A brooder or hover comprising a frame formed of outer side and end walls, means detachably securing said walls together, inwardly projecting upper and lower flanges carried by the upper and lower edges of said walls, a fabric inner wall for each of said outer walls, means dependingly supporting said fabric walls within said frame in spaced relation to the walls of said frame to provide insulating air spaces between the said outer and inner walls, and weighting means for certain of said fabric walls.

2. A brooder or hover comprising a frame formed of outer side and end walls disposed in connected relation, inwardly projecting upper and lower flanges carried by the upper and lower edges of said walls, a fabric inner wall for each of said outer walls, means dependingly supporting said fabric walls within said frame in spaced relation to the walls of said frame to provide insulating air spaces between the said outer and inner walls, weighting means for and carried by certain of said inner walls, and flaps depending from the said certain walls.

3. A brooder or hover comprising a frame formed of outer side and end walls, means detachably securing said walls together, inwardly projecting upper and lower flanges carried by the upper and lower edges of said walls, a fabric inner wall for each of said outer walls, means dependingly supporting said fabric walls within

said frame in spaced relation to the walls of said frame to provide insulating air spaces between the said outer and inner walls, weighting means for certain of said fabric walls, a heating member within the frame, a pair of transversely disposed supporting bars for said heating member, means dependingly securing said heating member to said bars, and means detachably securing said bars to said frame.

4. A brooder or hover comprising a frame formed of outer side and end walls, means detachably securing said walls together, inwardly projecting upper and lower flanges carried by the upper and lower edges of said walls, a fabric inner wall for each of said outer walls, means dependingly supporting said fabric walls within said frame in spaced relation to the walls of said frame to provide insulating air spaces between the said outer and inner walls, weighting means disposed intermediate the upper and lower ends of and carried by certain of said fabric walls, said weighting means substantially aligning with the lower flanges of certain of said outer walls, a heating member disposed longitudinally within said frame, a pair of transversely disposed supporting bars for said heating member, means detachably securing said heating member to said bars, a pair of inwardly projecting bar supporting elements carried by each of said side walls, each element having an opening, and a threaded stud carried by each bar at each end thereof engageable in an opening to thereby hold said outer side walls against spreading, the threads on said studs engaging the marginal edges of an opening to thereby resist movement of a stud relative to an element.

5. A brooder or hover comprising a frame formed of opposite side and end walls, pairs of vertically spaced apart leg guiding members carried by certain of said walls, a leg slideable in each pair of guiding members, a laterally projecting arm carried by each leg between said guiding members, and a plurality of vertically spaced apart downwardly directed hook members fixed to said certain walls, an arm being engageable with a selected hook member to thereby hold a leg in vertically adjusted position and maintain said frame at a predetermined height.

6. A brooder or hover comprising a frame formed of outer side and end walls, means slidably connecting the adjacent ends of said walls together, flexible inner side and end walls, upwardly opening channel members fixed to said outer side and end walls, upper tunnels carried by said flexible walls, a rod disposed in each upper tunnel and engageable in a channel member to dependingly support said inner walls in inwardly spaced relation to said outer walls, a pair of top sections engageable on the upper end of said frame, means hingedly securing said sections together, means carried by said outer walls holding said top sections against lateral and endwise movements, heat insulating means carried by said top sections, a pivoted supporting leg carried by an end of each top section and engageable with a holding means for holding a leg in upright position, a heating means within said frame, and a roost engageable with said top sections.

7. A brooder or hover comprising a frame, a heating means in said frame, means supporting said heating means in said frame, a pair of top sections engaging the upper end of said frame, upwardly projecting members carried by said frame for holding said top sections against lat-

eral and longitudinal movement, means hingedly securing said top sections together, each of said top sections comprising a bottom wall, upstanding side and end walls, a transverse partition and bracing member secured to a bottom wall and opposite side walls, and an insulating means carried by each of said sections, said partitions holding said insulating means against movement.

8. In a brooder or hover, a structure comprising a pair of sheet-like rigid outer side walls, a pair of sheet-like rigid outer end walls, said side and end walls having coacting means for detachably and slidably connecting adjacent ends of said walls together and for limiting the extent of the sliding movement in one direction of one wall with respect to an adjacent wall, a pair of vertically disposed flexible inner side walls, a pair of flexible inner end walls, said inner walls being formed from a web of woven fabric, means connected with the upper ends of said outer walls and to the upper ends of the said inner walls for detachably suspending said inner walls in opposed spaced relation with respect to the inner faces of said outer walls to provide for the correlation of said outer and inner walls to form insulating air spaces.

9. In a brooder or hover, a structure comprising a pair of sheet-like rigid outer side walls, a pair of sheet-like rigid outer end walls, said side and end walls having coacting means for detachably and slidably connecting adjacent ends of said walls together and for limiting the extent of the sliding movement in one direction of one wall with respect to an adjacent wall, a pair of vertically disposed flexible inner side walls, a pair of flexible inner end walls, said inner walls being formed from a web of woven fabric, means connected with the upper ends of said outer walls and to the upper ends of the said inner walls for detachably suspending said inner walls in opposed spaced relation with respect to the inner faces of said outer walls to provide for the correlation of said outer and inner walls to form insulating air spaces, and weighting means for and secured to the lower ends of said inner side walls.

10. In a brooder or hover, a structure comprising a pair of sheet-like rigid outer side walls, a pair of sheet-like rigid outer end walls, said side and end walls having coacting means for detachably and slidably connecting adjacent ends of said walls together and for limiting the extent of the sliding movement in one direction of one wall with respect to an adjacent wall, a pair of vertically disposed flexible inner side walls, a pair of flexible inner end walls, said inner walls being formed from a web of woven fabric, means connected with the upper ends of said outer walls and to the upper ends of the said inner walls for detachably suspending said inner walls in opposed spaced relation with respect to the inner faces of said outer walls to provide for the correlation of said outer and inner walls to form insulating air spaces, and flexible flaps depending from the lower ends of the inner side walls.

11. A brooder or hover comprising a rectangular frame-like structure formed of a pair of vertical oppositely disposed outer rigid side walls and a pair of vertical oppositely disposed outer rigid end walls, said walls being provided with correlated means at their ends for slidably connecting adjacent ends thereof together and to limit the downward sliding of one wall relative to an adjacent wall, a pair of flexible inner side wall forming elements, a pair of flexible inner

end wall forming elements, each of said elements having its upper terminal portion in the form of a tunnel, a channel member extending inwardly from the inner side of each rigid wall at the upper end of the latter, rods disposed in the tunnels of said elements and correlating with the channel members for dependingly supporting said elements inwardly of and in spaced relation to said rigid walls to thereby provide for the correlation of said elements and rigid walls to form insulating air spaces.

12. A brooder or hover comprising a rectangular frame-like structure formed of a pair of vertical oppositely disposed outer rigid side walls and a pair of vertical oppositely disposed outer rigid end walls, said walls being provided with correlated means at their ends for slidably connecting adjacent ends thereof together and to limit the downward sliding of one wall relative to an adjacent wall, a pair of flexible inner side wall forming elements, a pair of flexible inner end wall forming elements, each of said elements having its upper terminal portion in the form of a tunnel, a channel member extending inwardly from the inner side of each rigid wall at the upper end of the latter, rods disposed in the tunnels of said elements and correlating with the channel members for dependingly supporting said elements inwardly of and in spaced relation to said rigid walls to thereby provide for the correlation of said elements and rigid walls to form insulating air spaces, by certain of said elements intermediate their upper and lower ends, and certain of said rigid walls formed with inwardly extending flanges aligning with and directed towards said weights.

13. In a brooder an open top and bottom rectangular frame-like structure including rigid outer end walls, rigid outer side walls, flexible inner end walls suspended from and disposed in spaced relation to the inner faces of said outer end walls, flexible inner side walls suspended from and disposed in spaced relation to the inner faces of said outer side walls, spaced bracing means connected at their ends with the upper portion of said rigid side walls, and an insulated closure for the open top of said structure mounted on said bracing means and the upper ends of said rigid walls and formed of a pair of selectively shiftable sections hinged together and each provided with a supporting leg pivoted to the outer end thereof for seating on the top of a rigid end wall for supporting the section in an elevated position, and supporting means for said structure secured to said rigid outer end walls.

14. In a brooder provided with a heating means, a sectional flat top therefor, said sections hingedly secured together at their inner sides and each of said sections including bottom, side and end walls for forming an open top chamber for receiving loose material, means connected to each section for supporting each of said sections in an inclined position to thereby ventilate the brooder and regulate the intensity of the heat within the brooder chamber and means extending transversely of the chamber of each section for bracing the latter and arresting the shifting of the loose material.

15. In a brooder, a horizontally disposed suspended frame formed of side and end walls, a rectangular element formed of a pair of oppositely shiftable sections provided with open top chambers for receiving loose material, said element being mounted on said walls and constituting a closure for the top of said frame, a pair

of inwardly projecting apertured supporting members carried by an opposed pair of said walls, a pair of supporting bars extending between said pair of walls, depending pins carried by the opposite ends of said bars engageable in the apertures of said supporting members, a perforate heater housing, a pair of transverse bars fixed to said housing, and interengaging coupling members carried partly by said first pair of bars and partly by said second pair of bars for suspending said housing within said frame.

16. A brooder comprising a heating space, a top for said space, said top formed of a pair of oppositely shiftable like sections hingedly connected together, each section including a bottom, a pair of side and a pair of end walls, said side and end walls of each section coacting with the bottom of the section to form an open top chamber for receiving a loose material, the hinged connection between said sections being disposed at the inner end walls of the latter, and each of said sections including transversely extending bracing means within the chamber thereof, said means acting to arrest the shifting of the material within said chambers.

17. In a brooder, a substantially rectangular frame-like structure formed of rigid side and end walls, means correlating with said end walls for selectively suspending said structure at different levels, independent sheet-like fabric side and end walls inwardly of and disposed in spaced relation with respect to said rigid walls, said inner end walls being of greater height than said inner side walls, weighting means for said inner side walls arranged within the lower ends of the

latter, and freely movable overlapping flaps suspended from and offset with respect to the lower ends of said inner side walls.

18. In a brooder, an open framework constituting upright walls, supporting means for said framework spacedly maintaining the bottom edges of the latter with relation to a supporting surface, substantially horizontally disposed supporting means for supporting a heating element within the confines of said framework and extending between the upper portions of opposite walls, means engageable with said opposed walls for removably securing said heating element supporting means, heating means suspendably carried by the said heating element supporting means, a flat sectional approximately horizontally disposed removable heat conducting roof element spaced above said heating means independent therefrom and resting on said heating element supporting means, the top surface of said roof element constituting a floor for loose material, said roof element together with said upright walls constituting a downwardly opening brooding chamber, the heat transmitted through said roof serving to warm and dry any loose material thereon, said roof element being provided with means extending transversely thereof to hingedly connect the sections together and provide for holding the loose material from shifting from one section to another when one section is raised, and means extending transversely of each section for holding the loose material against shifting relative to a section.
